(75) Inventors: **Mary Beth Adams**, Antioch, IL (US); **Martin P. Defatte**, Racine, WI (US)

(73) Assignee: **S.C. Johnson & Son, Inc.**, Racine, WI (US)

(**) Term: **14 Years**

(21) Appl. No.: **29/212,974**

(22) Filed: **Sep. 10, 2004**

(51) LOC (8) Cl. **26-01**

(52) U.S. Cl. **D26/23**

(58) Field of Classification Search D26/9, D26/10, 22, 23; 431/292, 289

See application file for complete search history.

(57) **CLAIM**

The ornamental design for a melting plate with sun graphic cut-outs, as shown and described.

DESCRIPTION

FIG. 1 is an isometric view of the top of a melting plate with sun graphic cut-outs according to the present invention; FIG. 2 is an isometric view of the bottom thereof; FIG. 3 is an elevational view of the top thereof; FIG. 4 is an elevational view of the bottom thereof; and, FIG. 5 is an isometric view illustrating in phantom a candle holder in which the melting plate may be disposed. FIG. 5 is provided for context only and forms no part of the claimed design. Also, structures shown in phantom form no part of the claimed design.

1 Claim, 5 Drawing Sheets

CERTIFICATE OF CORRECTION

PATENT NO. : Des. 537,178 S

Page 1 of 1

APPLICATION NO. : 29/212974

DATED : February 20, 2007

INVENTOR(S) : Mary Beth Adams, Martin P. Defatte and Paul E. Furner

It is certified that error appears in the above-identified patent and that said Letters Patent is hereby corrected as shown below:

Title page, item (75) Inventors: replace "Mary Beth Adams, Antioch, IL (US); Martin P. Defatte, Racine, WI (US)" with --Mary Beth Adams, Antioch, IL (US); Martin P. Defatte, Racine, WI (US); Paul E. Furner, Racine, WI (US)--

Signed and Sealed this

Ninth Day of June, 2009

JOHN DOLL
Acting Director of the United States Patent and Trademark Office
